UNITED STATES PATENT OFFICE.

OTTO P. CRAMER, OF SAN FRANCISCO, CALIFORNIA.

LATCH.

Application filed June 18, 1927. Serial No. 199,641.

My invention relates to latches, and more especially to that type of latch adapted for use on cupboard doors.

An object of the invention is the provision of a latch for a light door, the body of the latch being adapted to be punched or otherwise formed from suitable sheet material.

Another object is the provision of a door latch having a latch pin adapted to be fixed to the door casing, and capable of adjustment to take up play and to adapt it to either flush or lip doors.

Another object is the provision of a latch so designed as to be reversible, so that it may be used on either right hand or left hand doors.

This invention possesses other objects and features of advantage, some of which, with the foregoing, will be set forth in the following description of the preferred form of my invention which is illustrated in the drawings accompanying and forming part of the specification. It is to be understood that I do not limit myself to the showing made by said drawings and description, as I may adopt variations of the preferred form within the scope of my invention as set forth in the claims.

Referring to the drawings:

30 Figure 1 is a front elevation of the latch and a portion of the door and door frame with which it is used.

Figure 2 is a vertical sectional view, the plane of section being indicated by the line 35 2-2 of Figure 1.

Broadly considered, my invention comprises a latch for cupboard or other light doors. The body of the latch may be formed by stamping from suitable sheet material, 40 and is apertured to receive a pivot pin adapted to be rigidly seated adjacent the edge of a door. A wing is provided on each side of the body so as to make the latch reversible, and therefore adapted for use on either right 45 or left hand doors. An adjustable latch pin is also provided to be positioned upon the door casing so that one of the wings can be brought into engagement with the latch pin to secure the door.

50 In greater detail my invention comprises a headed pivot pin, such as a wood screw 6, adapted to be driven rigidly into the outer face of a door 7, adjacent one of the edges thereof other than the hinged edge.

55 The body 8 of the latch, preferably stamped from a metal sheet, is apertured to enable it

to be mounted for pivotal movement upon the pin 6, and is provided upon its under side with a boss 9 having a face 11 of relatively large area, and preferably concentric with the pivot pin. This arrangement of the parts enables the body to be spaced away from the face of the door, thus obviating the necessity of a washer. The face 11 of the boss is preferably concave so that the area of contact between the latch and the door is a relatively narrow annulus surrounding the pivot pin, with the result that a minimum of frictional resistance is offered to movement of the latch.

An operating handle 12 is provided, preferably integral with the body and offset therefrom to space it from the door to facilitate grasping. A spring 14 for resisting the movement of the body is interposed between it and the door. This spring is preferably in the form of a broken circle surrounding the boss 9 and has its ends 16 bent upwards from the plane of the circle to be secured to the under side of the operating handle by the lugs 17. The spring is provided, opposite the break, with a loop 18 through which a suitable brad or screw 19 may be driven to secure the spring to the door. It is thus seen that the spring normally retains the latch with the operating handle 12 parallel with the adjacent edge of the door.

The body of the latch is provided with a recess 23 defined by the opposing shoulders 24 which are so spaced that they limit the rotation of the body by striking the head of the brad 19, which, in operating position, lies within the recess.

Formed preferably integral with and on opposite sides of the body are wings 26, one or the other of which is adapted to extend beyond the edge of the door. By the provision of these oppositely disposed wings a reversible latch is provided, applicable to either right or left hand doors.

A latch pin having a threaded shank 27 and a substantially hemispherical head 28, is adapted to be so positioned on the door casing 29 that it may be engaged by the extending wing. The head 28 is preferably provided with screw driver slots 31 to facilitate adjustment of the pin so that play between the head 28 and the wing is taken up, and so that the same equipment is adaptable to flush doors or to lip doors of varying thicknesses.

To open the door the latch has merely to be

rocked on its pivot pin to disengage the wing from the latch pin; and when the door is closed, the latch is automatically fastened by the wing sliding over the inclined surface of the head 28 of the latch pin until the wing is snapped under the head by the action of the spring.

I claim:

1. A door latch comprising a latch pin adapted to be adjustably fixed to the door casting; a headed pivot pin adapted to be fixed to the door; and a reversible body mounted for pivotal movement on said pivot pin and comprising an operating handle, a shoulder for limiting the movement of the body, wings on opposite sides of the body for engaging the latch pin, a boss for spacing the body from the door, and a spring interposed between the body and the door for urging the latch into position of engagement.

2. A door latch comprising a body adapted to be pivotally mounted to a door, a latching wing on said body, a handle on said body, a spring arranged between said body and its mounting for urging the wing into an engaged position, and a pin for securing said spring to the door, said pin cooperating with a recess formed in the body to form a stop against excess movement of the latch. 25

3. A door latch comprising a pivot pin 30 adapted to be fixed to a door, a body arranged for pivotal movement upon said pin, a boss on said body for spacing the body from the door, and a spring forming a broken circle surrounding said boss and having its ends 35 secured to said body and its center secured to the door.

In testimony whereof, I have hereunto set my hand.

OTTO P. CRAMER.
